UNITED STATES PATENT OFFICE.

ALFRED R. FENAES AND WILLIAM H. KENNEDY, OF HOUSTON, TEXAS.

LUBRICATING-OIL DISPENSER.

1,418,142.

Specification of Letters Patent. Patented May 30, 1922.

Application filed September 12, 1921. Serial No. 499,881.

To all whom it may concern:

Be it known that we, ALFRED R. FENAES and WILLIAM H. KENNEDY, citizens of the United States, residing at Houston, in the county of Harris and State of Texas, have invented certain new and useful Improvements in a Lubricating-Oil Dispenser, of which the following is a specification.

This invention relates to new and useful 10 improvements in a lubricating oil dispenser.

One object of the invention is to provide a liquid dispenser specially designed for dispensing lubricants and similar liquids, and which is formed with transparent container 15 tubes provided for the purpose of revealing to customers the character of the liquid dispensed.

Another object is to provide a safety attachment which will automatically cut off 20 the flow of liquid from the supply reservoir in case of breakage of any of the transparent tubes.

A further feature of the invention resides in the provision of means for heating the oil 25 in cold weather, or when the device is used in cold climates, so that the oil will readily flow and not change its appearance due to changes of temperature.

A still further feature resides in the provision of a novel construction whereby the 30 air may readily escape from the container tubes in filling the same, thus facilitating the process of filling.

With the above and other objects in view 35 this invention relates to certain novel features of construction, operation and arrangement of parts an example of which is given in this specification and illustrated in the accompanying drawings, wherein:—

40 Figure 1 is a side view of the complete device.

Figure 2 shows an enlarged fragmentary section view of the top part thereof.

Figure 3 shows a partial plan view.

45 Figure 4 shows an enlarged fragmentary plan view, and

Figure 5 shows an enlarged fragmentary vertical sectional view of the bottom part of the device.

50 Referring more specifically to the drawings, the numeral 1 designates the bottom casting forming a stand which is cast hollow and the numeral 2 designates the top casting which is also cast hollow. Anchored 55 to these top and bottom castings, and supported by the latter there is a container

tube 3 formed of glass or other transparent material.

The numerals 4 and 5 designate tubes which pass through the top casting and 60 communicate with the chamber 6 therein, and whose lower ends enter the chamber 7 in the bottom casting and are anchored to said casting.

It is to be noted that the ends of the container tube 3 are open and communicate 65 freely with the chambers 6 and 7.

The numeral 8 designates the supply reservoir which is connected into the upper end of the tube 4 through the pipe 9. This pipe 70 is controlled by the shut off valve 10. The filler tube 4 is formed with a valve cage 11, having a valve seat therein and beneath it said tube is formed into a float chamber 12. A valve 13 is confined in said 75 cage and controls said seat and has a depending stem 14 to the lower end of which the float 15, in said float chamber, is secured.

The float normally holds the valve elevated above the seat and permits the fluid 80 to flow from said reservoir and fill the container tube 3. Should said tube become broken the float and valve will descend, and the latter will rest on said seat and shut off the supply of oil and thus prevent waste. 85 When the container tube has been repaired the valve 13 may be lifted by means of the cable 16, which is attached thereto and which passes up through the upper end of the tube 4 and over the pulley 17 fixed 90 thereabove.

The upper end of the tube 5 is extended 95 above the level of the reservoir so as to permit the ready escape of air from the container 3 in filling the same.

Leading from the chamber 7, one on each side, are the delivery spouts 18, 18, which are controlled by the hand valves 19.

The bottom of the chamber 7 is formed into a heater casing 20, cast integral with 100 the casting 1, and provided to contain the heater coil 21. This coil is in a circuit 22 and the heater is controlled by the usual electrical thermostat 23. This heater warms the oil in the chamber 7 and it circulates 105 freely up through the container tube 3 and back down through the tubes 4 and 5 thus keeping the oil affluent in cold weather and maintain it at a uniform color. Otherwise when the oil becomes cold it becomes of a 110 milky color which injuriously affects the sale thereof to the ordinary purchaser.

What we claim is:—

1. An oil dispensing device including a tubular container, a reservoir, a tube leading from the reservoir and entering the bottom of the container and communicating also with the top thereof, and means controlling the flow of fluid through said tube, said means including a valve seat in the tube, a valve arranged to seat thereon, a float chamber underneath said seat and a float connected to the valve and located in said chamber.

15 2. A fluid dispensing device including a container tube formed of transparent material, a reservoir, tubes connected into the container tube at the top and bottom thereof, one of said tubes being extended upwardly and open at the top, the other tube being connected into the reservoir, said last mentioned tube being equipped with fluid controlling means including a valve seat a valve controlling the same, a float chamber and a float in said chamber connected to said valve.

25 3. A fluid dispensing machine including a transparent fluid container, provided with top and bottom chambers with which the container communicates, tubes connecting said chambers, one of which is extended above the top chamber and whose upper end is open, a reservoir into which the upper end of the other tube is connected, means for controlling the flow of fluid from said reservoir into said last mentioned tube.

30 4. A fluid dispensing machine including a transparent fluid container, provided with top and bottom chambers with which the container communicates, tubes connecting said chambers, one of which is extended above the top chamber and whose upper end is open, a reservoir into which the upper end of the other tube is connected, means for controlling the flow of fluid from said reservoir into said last mentioned tube, and

45 a heating element arranged in the bottom chamber.

5. A fluid dispensing machine including a transparent fluid container, provided with top and bottom chambers with which the

50 container communicates, tubes connecting said chambers, one of which is extended above the top chamber and whose upper end is open, a reservoir into which the upper end of the other tube is connected, means for controlling the flow of fluid from said reservoir into said last mentioned tube, said means including a float chamber formed in said tube, a valve seat therein above said float chamber, a valve above the seat and a float in said float chamber connected to 60 said valve.

6. A fluid dispensing machine including a transparent fluid container, provided with top and bottom chambers with which the container communicates, tubes connecting 65 said chambers, one of which is extended above the top chamber and whose upper end is open, a reservoir into which the upper end of the other tube is connected, means for controlling the flow of fluid from said reservoir into said last mentioned tube, said means including a valve mechanism arranged to close by gravity and means operated by the fluid in said last mentioned tube to open 70 said valve.

7. A fluid dispensing machine including a transparent fluid container, provided with a top and bottom chambers with which the container communicates, tubes connecting said chambers, one of which is extended 80 above the top chamber and whose upper end is open, a reservoir into which the upper end of the other tube is connected, means for controlling the flow of fluid from said reservoir into said last mentioned tube, said means including a valve mechanism arranged to close by gravity and means operated by the fluid in said last mentioned tube to open 85 said valve, and a manual device connected to said valve for also opening the same.

90 In testimony whereof we have signed our names to this specification in the presence of two subscribing witnesses.

ALFRED R. FENAES.
WILLIAM H. KENNEDY.
